UNITED STATES PATENT OFFICE.

WARREN FUHRMANN, OF WESTFIELD, NEW JERSEY, ASSIGNOR TO ADDOMETER CORPORATION, OF NEW YORK, N. Y., A CORPORATION OF DELAWARE.

FULL-STROKE DEVICE FOR CALCULATORS.

1,232,019.

Specification of Letters Patent.

Patented July 3, 1917.

Application filed September 30, 1916. Serial No. 122,979.

To all whom it may concern:

Be it known that I, WARREN FUHRMANN, a citizen of the United States, and resident of Westfield, in the county of Union and 5 State of New Jersey, have invented certain new and useful Improvements in Full-Stroke Devices for Calculators, of which the following is a specification.

This invention relates to calculating or 10 similar machines of the character in which a main operating member is provided which is connected with the mechanism operated thereby, such as a main shaft, by means of a flexible or spring connection that is designed to permit a yielding effect during 15 rapid operation of the main operating member, whereby the parts of said mechanism are not forced to operate at the same speed as the operating member, but may move at 20 a slower speed; the force exerted by said main operating member being stored up in said flexible or spring connection so that the full and complete movement of the retarded parts of the mechanism is insured.

25 The invention mainly consists in the provision of a pair of reversing pawls that will compel full movement in both the advance and return of the handle and parts operated thereby, in connection with which one 30 of the pawls is provided with means for arresting the handle and certain parts when fully advanced by rapid stroke in which the main shaft is retarded, by means of resilient connections whereby the handle is held in 35 the forward position until the main shaft and other parts complete their forward or advanced movement, whereupon this pawl will release the handle and permit the several parts to return to normal position.

40 In the drawings showing one embodiment of my invention, Figure 1 is a side elevation with the parts in normal position. Fig. 2 is a similar view with the handle and segment fully advanced but the pitman retarded. Fig. 3 is a partial horizontal section looking upward as seen on the line 3-3 of Fig. 1. Fig. 4 is a partial view similar to Fig. 2 but with the segment and pitman fully advanced. Fig. 5 is a plan 45 view of the parts shown in Fig. 4. Fig. 6 is a horizontal section on the line 3-3 of Fig. 1; and Figs. 7 and 8 are details of the parts for controlling the reversing pawls.

50 The construction illustrated is especially designed for use with the flexible handle

pull and controlling parts as set forth in a pending application, Serial No. 54,313, but is applicable to other constructions of machines of this character.

As shown in the drawings I provide a 60 crank 2 fast on an operating shaft 40, that swings in the side plate 1. A pitman 3 is pivoted to the crank 2 and extended rearward to connect with a crank 4 fast on a main shaft 5 at the rear.

65 The machine is operated by a handle 23 fast to a short spindle 24 that rocks in bearings 25, and which spindle carries a segment 26. This segment has a notched periphery co-operating with two pawls 27 and 28 that 70 alternately act to compel full stroke of the handle, in each direction. When the handle is drawn forward the pawl 27 falls successively in the segment notches and will prevent reverse movement of the handle and 75 segment until the end of the stroke is reached, when by certain means this pawl is thrown up to free the segment therefrom, for its return by the actuating means. During the return movement of the handle and 80 segment the pawl 28 is permitted to fall successively into the notches 55 and prevent the handle being drawn forward again during the return movement, until the segment and handle reach the end of the return 85 stroke. It is to be understood that the spindle 24 is free from the front shaft 40, and only connected therewith by mechanism hereinafter set forth.

85 A bar 30 has one end pivoted on the segment 26 to be moved back and forth by the handle. The rear end of the bar 30 is connected by one or more springs 31 with the pitman 3, and these springs are held under tension by reason of a pin 32 on the pitman, 90 3, extending into a slot 33 in the bar 30, the springs holding the pin normally against the forward end of the slot, as shown in Figs. 1 and 2. By this means when the handle is drawn forward to swing the segment 26, the bar 30 will draw the pitman 3 forward through the springs 31, and under normal conditions these springs will not stretch; but if the handle is drawn rapidly to its forward position, the springs will 95 yield to the resistance of the crank 4 and the pitman 3 will advance later than the bar 30, and hence the pin 32 will move back in the slot 33, as indicated in Fig. 2.

100 The rear end of the bar 30 contains a slot 110

35 in which slides a stud 36, fast to one end portion 37 of a plate or frame 38, shown separately in Fig. 6. The other end of the plate 38 contains a slot 39, in which slides the crank pin 10, so that the plate may have a sliding movement on the crank pin, the plate being guided by the head on the crank pin 10. Pin 10 moves in a slot 11 in pitman 3. The plate 38 has an open portion 10 41, being in the form of a frame, so that springs 31 can freely operate upon the pitman 3. This plate 38 is shown as provided with extensions 43 and 44 to which are secured the main springs 45 and 46 of the machine; the rear ends of these springs being secured to studs 47 and 48 on the side plate 15 1. These springs will draw the plate 38 rearwardly, and its slotted rear end 39 will engage the crank pin 10 and move the crank 20 to the limit of its rearward position. The bar 30 is shown provided with a pair of arms 50 and 51, that carry springs 52 and 53 extending rearward and connected with the end member 37 of the plate 38. But 25 these springs are weak in their operation compared with the springs 31 connecting the pitman and bar 30.

When the handle and segment 26 are moved forward to the limit of the advance 30 movement, the pawl 27 will engage a notch 56, (see Fig. 2) and lock the segment and handle in this position. Since the bar 30 pivoted to the segment 26, is connected with the pitman 3 by springs 31, if the handle is 35 drawn quickly forward these springs will stretch and the pitman will have a retarded advance. This will cause the pin 32 to move rearward in the slot 33 as indicated in Fig. 2. Means are provided controlled by the 40 pitman 3, for holding the pawl 27 in the locking position of Fig. 2, until the pitman advances its full stroke, whereupon this pawl 27 is swung to release the segment. As shown I provide a lever 57 pivoted on the 45 pin 7 of the pawl 27 and normally drawn rearward by a spring 58, the arm 59 of this lever engaging a pin 60 on the pawl that will raise the pawl from the segment. The spring 58 is much stronger than the spring 50 61 that draws the pawl against the segment, hence when the lever 57 is not restrained it will hold the pawl 27 away from the segment. A latch 62 has a notched end 6 arranged to engage a rear shoulder 63 on the 55 lever 57, and is pressed to this position by a spring 64. In the normal position of Fig. 1 the latch 62 will hold the lever 57 in the forward position to free the pawl 27, and permit the pawl to be drawn against the 60 notched segment to engage its notches during the forward movement of the segment. But when the pitman 3 is drawn fully forward, a stop arm 65 fast thereon will strike an arm 66 on the latch 62 and move it to release the lever 57. Hence this lever will be

drawn by its spring to swing pawl 27 from the segment 26. This is effected at the end of the forward stroke of the pitman 3. It will thus be seen that the segment 26 will be held in the forward position when the pitman is retarded, until the pitman completes its forward stroke, when the pawl will release the segment. However, in the normal operation the pitman 3 moves forward in unison with the bar 30 and hence at the 75 end of the stroke the pawl 27 will be at once raised from the segment.

At the end of the return stroke of the segment 26, a pin 77 on the segment will strike an arm 78 of the lever 57, and swing the 80 lever to tension its spring 58, and permit the lever to be relatched by the latch 62, thus releasing the pawl 27 to be drawn against the segment by its spring 61.

Means are provided whereby the other 85 pawl 28 is raised from the segment 26 during the forward stroke, and released to operate during the return stroke. A lever 67 is mounted on the pivot 8 of the pawl 28 and engages a pin 68 on the pawl 28 to hold the 90 pawl from being pressed by its spring 69 against the segment. The lever 67 has an arm 70 whose pointed extremity engages in notches in an arm 71; which arm is pressed against the arm 70 by a spring 72, whereby 95 the lever 67 is held in either of the two positions. In the position shown in Fig. 1 the pawl 28 is held away from the segment, but at the end of the forward stroke of the pitman 3, a stop arm 73 fast on the pitman 100 strikes an arm 75 on the lever 67 to shift this lever to its other notch engaging position, that will permit the pawl 28 to be drawn against the notched segment. At the end of the return stroke of the segment, a pin 105 74 on the segment will strike the arm 75 and swing the lever 67 to its former position, that will raise the pawl 28 from the segment 26.

The operation of these parts is as follows: 110 The main springs 45, 46 always exert a rearward draft on the plate 38, and in its normal position, this plate engaging the crank pin 10, holds the crank and shaft 5 at the limit of its movement. The springs 31 tensioned between the bar 30 and the pitman 3, retain these members with the pin 32 engaging the forward end of the slot 33 in the bar. The springs 52 and 53 that are tensioned between the arms on the bar 30 115 120 and the plate 38, since they are much weaker than the main springs, 45, 46, will draw the bar 30 rearward. The bar 30 being connected with the pitman 3 through the springs 31, the bar and pitman will be both moved 125 rearward until the pitman has the forward end of its slot 11 engaged by the crank pin 10, that will limit the rearward movement of the pitman. The connection between the bar 30 and the plate 38, by stud 36 on the 130

plate riding in slot 35 on the bar, is so arranged that in the described position of the parts, this stud is at the forward portion of the slot 35.

5 Upon drawing the handle and segment plate 26 forward from the normal position, by a slow movement, the bar 30 will be carried forward. The springs 31 connecting the bar 30 with the pitman 3, will cause the 10 bar and pitman to move forward in unison, and the bar at this initial movement will draw forward on the light springs 52 and 53; but the latter connecting with the plate 38, will not advance this plate because of the much greater opposed tension 15 of the main springs 45 and 46. Hence the plate 38 and stud 36 will remain stationary until the slot 35 in the bar 30 moves on the stud and its rear end engages the stud, 20 whereupon the bar 30 will from this time forward cause the plate 38 to move ahead in unison therewith. But the initial movement of the bar 30 and pitman 3, since the plate 38 holds the crank pin 10 in its rear position at such time, will cause the movement of the slotted end 11 of the pitman on the crank pin 10. This movement of the crank pin 10 in the slot 11 is identical with that of the stud 36 in the slot 35; 25 whereupon as soon as the bar 30 has advanced sufficient to carry the plate 38 ahead with it, the pitman 3 will have advanced its slot sufficient to engage the crank pin, and cause the crank 4 to be advanced by 30 the pitman. This will have the effect of causing the slotted end 39 of the plate 38 to advance in unison with the forward movement of the crank pin 10 that rides in such slot. These several parts will continue their 35 forward movement in unison to the end of the stroke. When the handle is released, the springs 45, 46, will return the parts in the same relative positions in which they advanced after the said initial movement; 40 until the crank 4 reaches the limit of its return movement, that will arrest the rearward movement of the plate 38. But the tension of the springs 52, 53, will draw rearward on the bar 30, that will cause its 45 rear slotted end 35 to move rearward on the stud 36. And it will be understood that the pitman 3 will partake of this additional rearward movement of the bar 30, so that the pitman will have a rearward movement and its slotted end 11 will move to the rear 50 on the crank pin 10, that will bring these parts to their former positions.

When the handle and bar 30 are drawn forward rapidly, the resistance of the parts connected with the shaft 5, will cause the pitman 3 to advance slower than the movement of the bar 30; which is permitted by the stretching of the springs 31 connecting the bar and the pitman. But it is to be 55 understood that the initial movement of the

bar 30 will cause the pitman 3 to move in unison therewith until the crank pin 10 reaches the other end of the slot 11 in the pitman 3, that will serve to retard the advance of the pitman, after it and the bar 70 have made this initial movement in unison. The further advance of the bar 30, as stated, will stretch the springs 31, but the plate 38 after the said initial movement will be carried along with the bar 30 by the 75 stud 36. Hence the plate 38 will move forward while the crank pin 10 and pitman will have a retarded movement, causing a rearward movement of the crank pin relative to the slotted end 39 of the plate. As 80 soon as the handle and bar 30 reach the limit of the forward position, the latch pawl 27 will engage the segment 26, and lock the bar 30 in the forward position, (see Fig. 2). The plate 38 will also be locked 85 in this forward position, but the now extended springs 31 will cause the further advance of the pitman 3 for the limit of its forward movement, that will insure the full movement of the crank 4 and connected 90 parts. The pitman 3 will move forward until the stud 32 reaches the end of the slot 33, during which movement stop 65 on the pitman will strike the latch 62 and shift it to 95 free the pawl 27, to release the segment. This will release the bar 30 and connected parts, that will return to their normal positions, as has been set forth.

In the normal position as shown in Fig. 1 it will be seen that the pawl 28 is elevated 100 from the segment. As the pitman reaches the end of its forward stroke, the arm 73 thereon will strike the arm 75 of the lever 67, causing this lever to swing and permit the pawl 28 to be swung down on the segment with its pin 68 now free from the lever 67. Therefore, during the return stroke the pawl 28 will successively fall in the notches and prevent advance of the segment. At the end of the return stroke the 110 pin 74 on the segment will engage the arm 75 and swing the lever 67 that will engage the pin 68 on the pawl 28 to raise the pawl from the segment. The arm 70 of the lever 67 will engage alternately the two notches 115 of the arm 71, and retain the lever in the two said positions.

In a normal operation of the machine when the handle is pulled forward at the usual rate of speed, the springs 31 do not 120 stretch, and the pitman 3 and the bar 30 remain relatively stationary during the advance movement. When the handle reaches the limit of the forward stroke the pawl 27 would tend to fall back of the notch as 125 indicated in Fig. 2 and lock the segment in the forward position and hold all these parts in these positions. But at the latter part of the forward stroke the stop 65 will strike the latch 62 and swing the latch to 130

release the lever 57. The arm 59 on the latter will engage the pawl 27 and lift the pawl free from the segment. This is done at the latter part of the forward stroke and hence the segment 26 will not be locked in the forward position. It is only upon abnormal pull of the handle that the springs 31 stretch causing the retarded advance of the pitman, whereupon the pawl 27 holds the segment and handle forward until the pitman completes its retarded forward stroke when the segment is released.

Having thus described my invention what I claim is:—

1. The combination of a toothed segment, a handle attached to the segment, an operating bar, a spring connection between the bar and the segment, a swinging pawl, a spring arranged to hold the pawl against the segment, means arranged to overcome the spring and hold the pawl away from the segment, means arranged to disable said holding means at the end of the return stroke of the segment, means arranged to restore said holding means at the final part of the advance of the operating bar, whereby to free the pawl from the segment.

2. The combination of a toothed segment, a handle attached to the segment, an operating bar, a spring connection between the bar and the segment, a swinging pawl, a spring pressing the pawl against the segment whereby when the segment is drawn forward the pawl will engage the segment to prevent reverse movement thereof, a spring lever arranged to engage said pawl to swing it away from segment-engaging position, a latch arranged to engage said spring lever to hold it in position to release said pawl for engagement with the segment, a stop on said operating bar arranged to engage said latch at the final portion of the advance movement of the bar to swing the latch and free the spring lever, to swing the pawl to free the segment, and means to restore the spring lever to said latched position at the end of the return stroke of the bar.

3. The combination of a toothed segment, a handle attached to the segment, an operating bar, a spring connection between the bar and the segment, a swinging pawl, a spring pressing the pawl against the segment whereby when the segment is drawn forward the pawl will engage the segment to prevent reverse movement thereof, a spring lever arranged to engage said pawl to swing it away from segment-engaging position, a latch arranged to engage said spring lever to hold it in position to release said pawl for engagement with the segment, a stop on said operating bar arranged to engage said latch at the final portion of the advance movement of the bar to swing the latch and free the spring lever, to swing the

pawl to free the segment, and a stop on the segment arranged to engage the spring lever at the end of the return stroke of the bar to return the spring lever to latched position holding the pawl away from the segment.

4. The combination of a toothed segment, a handle attached to the segment, an operating bar, a spring connection between the bar and the segment, a swinging pawl, a spring pressing the pawl against the segment whereby when the segment is drawn forward the pawl will engage the segment to prevent reverse movement thereof, a spring lever arranged to engage said pawl to swing it away from the segment-engaging position, a latch having a notched end arranged to engage said spring lever to hold it in position to release said pawl for engagement with the segment, a spring tending to hold the latch in said latter position, an arm on said latch, a stop on said bar arranged to engage said latch arm at the final part of the advance of the bar to swing the latch and shift its notched end against the force of said spring away from the spring lever and permit the spring lever to shift the pawl away from the segment, an arm on the spring lever, and a stop on the segment arranged to engage said latter arm at the final portion of the latter stroke of the segment whereby to relatch the spring lever to free the pawl.

5. The combination of a toothed segment, a handle attached to the segment, an operating bar, a spring connection between the bar and the segment, a swinging pawl, a spring pressing pawl against the segment whereby when the segment is drawn forward the pawl will engage the segment to prevent reverse movement thereof, a spring lever arranged to engage said pawl to swing it away from segment-engaging position, a latch arranged to engage said spring lever to hold it in position to release said pawl for engagement with the segment, a stop on said operating bar arranged to engage said latch at the final portion of the advance movement of the bar to swing the latch and free the spring lever, to swing the pawl to free the segment, means to restore the spring lever to said latched position at the end of the return stroke of the bar, a second pawl, a spring pressing the second pawl against the segment to prevent reverse movement of the segment during return stroke of the handle and segment, a lever arranged to engage the second pawl to hold it free from the segment, means to swing said lever to free the second pawl at the end of the advance stroke of the bar, and means to swing said latter lever at the end of the return stroke of the operating bar to shift the second pawl away from the segment.

6. The combination of a toothed segment, a handle attached to the segment, an oper-

ating bar, a spring connection between the bar and the segment, a swinging pawl, means arranged to hold the pawl away from the segment, means arranged to disable said holding means at the end of the return stroke of the segment, means arranged to restore said holding means at the final part of the advance of the operating bar, whereby to free the pawl from the segment, a second pawl, a spring pressing the second pawl against the segment to prevent reverse movement of the segment during return stroke of

the handle and segment, a lever arranged to engage the second pawl to hold it free from the segment, means to swing said lever to free the second pawl at the end of the advance stroke of the bar, means to swing said latter lever at the end of the return stroke of the operating bar to shift the second pawl away from the segment, an arm on said lever, and a double notched strip that is spring pressed against said arm to retain it in the two said positions.

WARREN FUHRMANN.
